Roth & Lee,

Wool-Washing Machine,

N° 11,329.

Patented July 18, 1854.

UNITED STATES PATENT OFFICE.

J. A. ROTH AND JOSEPH LEA, OF PHILADELPHIA, PENNSYLVANIA.

MACHINE FOR WASHING PIECE GOODS.

Specification of Letters Patent No. 11,329, dated July 18, 1854.

To all whom it may concern:

Be it known that we, J. AUGUSTUS ROTH and JOSEPH LEA, have invented a new and useful Improvement in the Construction of 5 Apparatus for Washing Woven Fabrics in Continuous Sheets; and we do hereby declare that the following is a full, clear, and exact description of the same, reference being had to the annexed drawings, in which—

10 Figure 1 represents a transverse vertical section of a vat furnished with our improved washing apparatus. Fig. 2 is a longitudinal vertical section of the same, and Fig. 3 is a view of the fan wheel or dasher detached 15 from the vat.

Heretofore woven fabrics have been washed by being passed through vessels furnished with a continuous supply of fresh water, either twisted into a rope or in single sheets and have only been acted upon by 20 mere rinsing or squeezing.

Our improvement consists in an arrangement of rollers and of revolving dashers in combination with a vat whereby several continuous layers of cloth can be simultaneously passed through and acted upon by the water; thus effecting an economy in time and room and securing a more thorough washing of the material.

30 A, B, C, D, Fig. 2, represents a longitudinal vertical section of the improved washing vat.

E, F, G, H, Fig. 2, is a transverse vertical section of the frame inserted in said vat. 35 The frame E F G H is made of wood and extends the whole length inside of said vat. To this frame a series of wooden and metallic rollers $a' a'' a''' a''''$ and a lower series $b' b'' b''' b''''$, &c., are attached.

40 K and L are a pair of drawing and squeeze rollers for the purpose of drawing the fabric into the vat. M and N are also drawing and squeezing rollers for the purpose of drawing the fabric through the vat.

45 The fabric enters at K and L in five parallel and continuous layers, passes over the roller a and under the roller b . The upper layer of fabric passes around b' ascends and passes over a' ; the second layer passes around b'' ascends and passes over a'' ; the third layer passes around b''' ascends and passes over a''' ; the fourth layer passes around b'''' and a'''' ; the fifth passes around

b'' and a'' . As these layers pass over $a' a'' a''' a'''' a'''' a''''$ respectively they meet and move 55 on together through the drawing and squeeze rollers M and N.

$c' c'' c''' c'''' c''''$ &c. are a series of small dashers composed of a metallic shaft with wings or vanes v, v, v, v , extending radially 60 outward. These vanes are made of sheet iron or copper and are attached to the metallic shaft. These dasher wheels so made are placed in the respective positions shown at $c' c'' c''' c'''' c''''$ Fig. 2. They have pulleys at their extremities and are geared to the machinery so as to revolve rapidly. The level of the water is kept just below the axle of the dasher wheels. As the fabrics in single continuous layers pass along by the 70 dasher wheels the rapid revolution of the dasher wheels drives the water through the single thickness of fabric and thus rapidly and effectively cleanses it.

The operation of our improved washing 75 vat is as follows: The fabrics in five parallel and continuous layers enter between K and L; the layers are distributed and pass around the rollers $b' b'' b''' b'''' b''''$ and over $a' a'' a''' a'''' a''''$ as shown in 80 the drawing Fig. 2. Each layer is separately exposed to the action of the water in the vat; and as each one passes the revolving dasher wheels $c' c'' c''' c'''' c''''$ the water is thereby forcibly driven through or 85 against each separate layer. Afterward the five layers of fabric together pass between the drawing and squeezing rollers M N and are squeezed. The water is constantly changed in the vat in the ordinary 90 manner. The number of rollers and dasher wheels may be changed without altering our invention provided the same arrangement and combination of parts be preserved.

What we claim and desire to secure by 95 Letters Patent is—

The combination of the series of distributing rollers $a' a''$ &c., $b' b''$ &c., and the dasher wheels $c' c''$ &c., with the vat in the manner and for the purpose substantially as hereinbefore described.

J. A. ROTH.
JOS. LEA,
